US0D1062081S

(12) **United States Design Patent** (10) **Patent No.:** **US D1,062,081 S**
(45) **Date of Patent:** **** Feb. 11, 2025**

(54) **SET OF BEEHIVE GUARDS**

(71) Applicant: **Alcom New Zealand Limited**,
Motueka (NZ)

(72) Inventor: **Russell Eustace Smith**, Motueka (NZ)

(73) Assignee: **Alcom New Zealand Limited**,
Motueka (NZ)

(**) Term: **15 Years**

(21) Appl. No.: **29/836,757**

(22) Filed: **Apr. 28, 2022**

(30) **Foreign Application Priority Data**

Oct. 28, 2021 (NZ) 429606

(51) **LOC (15) Cl.** **30-99**

(52) **U.S. Cl.**
USPC **D30/199**

(58) **Field of Classification Search**

USPC D30/108-109, 121, 127, 199; 449/3, 32,
449/7, 8
CPC A01K 47/06; A01K 47/00; A01K 47/02;
A01K 47/04

See application file for complete search history.

(57) **CLAIM**

The ornamental design for a set of beehive guards, as shown and described.

DESCRIPTION

FIG. 1 is an isometric view of a first article, showing our new design;

FIG. 2 is a top view of the first article;

FIG. 3 is a front view of the first article;

FIG. 4 is a left side view of the first article;

FIG. 5 is an isometric view of a second article, showing our new design;

FIG. 6 is a front view of the second article;

FIG. 7 is a left side view of the second article;

FIG. 8 is a side view of the second article;

FIG. 9 is an isometric view of a third article, showing our new design;

FIG. 10 is a top view of the third article;

FIG. 11 is a front view of the third article; and,

FIG. 12 is a left side view of the third article.

1 Claim, 9 Drawing Sheets
